UNITED STATES PATENT OFFICE.

ERWIN S. GRAVER, OF PHILADELPHIA, PENNSYLVANIA.

TRAIN-SIGNAL SYSTEM.

SPECIFICATION forming part of Letters Patent No. 351,759, dated November 2, 1886.

Application filed June 29, 1886. Serial No. 206,597. (No model.)

To all whom it may concern:

Be it known that I, ERWIN S. GRAVER, a citizen of the United States, and a resident of Philadelphia, in the county of Philadelphia and State of Pennsylvania, have invented certain new and useful Improvements in Train-Signal System, of which the following is a complete, clear, and exact description, setting forth in general and in detail my invention.

10 My invention relates to improvements upon electric signals adapted to take the place of the usual bell and bell-rope.

The object of the invention is to provide improved means of doing away with chemical batteries, which are objectionable on account 15 of the corrosive action of the vapors given off.

The invention consists of the combination of elements particularly described in the sequel and claimed in the claims.

20 In order to illustrate the practical manner of carrying out the invention, and to enable others skilled in the art to which the invention appertains to make and use the same, drawings are hereunto annexed and described, 25 in which similar letters represent corresponding elements, and in which each part referred to is designated by a single character.

Figure 1 is a side view of the mechanism for operating the electrical generator. Fig. 2 is 30 a top view of the same, showing also the generator. Figs. 3, 4, and 5 are different views of the coupling. Fig. 6 is a general view of a railway-train to show how the invention is practically applied, and Fig. 7 shows a diagram intended to illustrate the nature of the electrical circuit-connections.

Referring to Figs. 1 and 2, the device therein shown consists of the combination of a magneto-electric generator or dynamo-electric machine, A, a ratchet, B, fixed upon the shaft C of said dynamo, a lever, D, having a hole through which passes loosely said shaft, a pawl, E, upon said lever and gearing into said wheel, a rectilinear spring, F, fixed at one end 40 to a stud, G, adjacent to said shaft, and at the other end connected to said lever upon the projection H, and an electric circuit represented in part by the line I, provided with two terminal springs, J, adjacent to said lever.

50 Referring to Fig. 3, where the coupling is

shown in side view in a separated condition, to Fig. 4, where a top view of one of the parts is shown by itself, and to Fig. 5, where the two parts (identical to each other) are shown coupled, the device is seen to consist of the 55 combination of two wedge-shaped metallic pieces or terminals, K, each provided at the smaller end with a circular hole, L, and a slot, M, and at the larger end with a projecting pin, N, having a head or enlarged portion, O, the 60 said pin fitting into said slot.

Referring to Fig. 6, the system there shown consists of the combination of a locomotive, P, railway-cars Q, a railway, R, an electric bell, S, or similar signal in the locomotive, a 65 circuit, I, passing through said bell, through the coupling shown in Figs. 3, 4, and 5, through the switch and dynamo shown in Fig. 1, through the wheels T, and into the track. The dynamo is not seen in Fig. 6; but the lever D is shown 70 as connected to a cord, U, which runs through the length of each car.

By the disposition above explained, and as shown in Fig. 7, the dynamos are adapted to be connected up in multiple arc between the 75 wire passing through the cars and the track located underneath the train. The electric circuits are shown more clearly in Fig. 7.

It is evident that when the lever is pulled in the direction of the arrow the ratchet E engages in the ratchet-wheel G and rotates the armature of the dynamo, generating a current which passes through the circuit I, simultaneously closed by the lever, which is of conducting material, pressing upon the springs 80 or terminals J. Upon releasing the lever it is withdrawn to its normal position (shown in Fig. 1) by the spring F, thereby both breaking the circuit and stopping the dynamo. When the conductor of the train is at the left 85 end of the car, he may operate the lever by the cord U.

The coupling may be put together by bringing the two pieces K in such relative positions, as shown in Fig. 3, that the pin-heads O will 90 pass through the circular holes L. By pulling them in opposite directions, the pins lock 95 themselves in the slots, as shown in Fig. 4.

The invention is not limited to the precise construction hereinbefore described, as it is 100

evident that many modifications may be made therein without departing from the spirit of the invention.

Having now stated the title, object, and nature of the said invention, having described its practical realization by reference to the accompanying drawings, having particularly ascertained the manner in which the same operates to accomplish the said object, what I consider to be novel and original, and therefore claim as my invention, is—

1. In a railway-train-signaling system, an electric-receiving apparatus located in the locomotive, in combination with magneto or 15 dynamo electric generators, one on each car, and a circuit-closing device, forming also a lever for operating the generator, substantially as and for the purpose set forth.

2. In a railway-train-signaling system, a receiving apparatus located on the locomotive, in combination with a series of generators, one on every car, and a circuit-closing device operatively connected with each generator, the 25 said circuit-closing device having attached to it a cord which runs through the car, substantially as and for the purpose set forth.

3. In a railway-train-signaling system, a signal-receiving apparatus on the locomotive, in combination with a series of generators located one on every car, and a circuit-closing 30 lever carrying a pawl which engages with a

ratchet-wheel on the shaft of the generator, substantially as and for the purpose set forth.

4. In a magneto train-signal, the combination, with a magneto-electric generator, of a 35 ratchet-wheel fixed upon the shaft of said generator, a lever having a hole through which passes loosely said shaft, a ratchet upon said lever and gearing into said wheel, a rectilinear spring fixed at one end to a point adjacent to 40 said shaft and at the other end connected with said lever, and an electric circuit having terminals adjacent to said lever, which is of conducting material and normally out of contact with said terminals. 45

5. In a magneto train-signal, the combination, with a generator-circuit and signal therein, of coupling in said circuit, consisting of two wedge-shaped terminals, each provided at the smaller end with a circular hole and a slot, 50 and at the larger end with a projecting pin having a head or enlarged portion, the said pins fitting into said slots, substantially as and for the purpose described.

In testimony whereof I have hereunto signed 55 my name and affixed my seal, in the presence of two subscribing witnesses, this 23d day of June, 1886.

ERWIN S. GRAVER. [L. S.]
